Inventor
ROCKWELL A. LOOMIS

By Franklin H. Stough
Attorney

UNITED STATES PATENT OFFICE.

ROCKWELL ADDISON LOOMIS, OF GUATEMALA, GUATEMALA.

SHARPENING IMPLEMENT.

Application filed February 17, 1922. Serial No. 537,172.

To all whom it may concern:

Be it known that I, ROCKWELL A. LOOMIS, a citizen of the United States, residing at Guatemala city, Guatemala, Central America, have invented certain new and useful Improvements in Sharpening Implements, of which the following is a specification, reference being had therein to the accompanying drawings.

10 This invention relates to sharpening implements and especially to an implement for sharpening cutlery, such as knives, razors or the like, but not limited in its scope or utility to such association.

15 An object of the invention is to provide an implement having abutting, abrading or grinding members presenting an angle therebetween of the required angle for the edge desired between which the implement 20 is moved or drawn and with improved means for holding such abrading members in such engaging position.

A further object of the invention is to provide a handle having a member slideable 25 and adjustable therein, extending to form jaws between which are engaged abrading members held at an angle relative to each other and between which a knife, razor or the like is moved or drawn to abrade and 30 sharpen both sides of the cutting edge simultaneously.

With these and other objects in view, the invention comprises certain novel parts, elements, features, combinations and arrangements as disclosed in the drawings together 35 with mechanical equivalents thereof as will be hereinafter more fully described and claimed.

In the drawings:

40 Figure 1 is a view partly in edge elevation and particularly in diametrical section showing the construction and arrangement of parts forming the present invention.

45 Figure 2 is a view in side elevation from the side indicated by arrow 2 at Figure 1.

Like characters of reference indicate corresponding parts throughout the several views.

The improved sharpening implement 50 which forms the subject matter of this application comprises a pair of jaw members 10 of similar or identical construction having recesses 11 formed therein, in their proximate faces, for the receipt of abrading or sharpening members 12. It is obvious that 55 these abrading or sharpening members 12

may be of any usual and ordinary material employed for the purpose and it is desired that said members shall be held in such relation to each other as to present an angle 60 indicated at 13 between which the edge of a knife, razor or the like may be moved or drawn, such angle corresponding to the angle of grinding at the edge of the device to be sharpened.

65 The means for maintaining the members 12 in such relation consists of a tube 14 serving also as a handle into which the ends of the jaw members 10 are inserted, such ends being provided with threaded sections 15.

70 Into the end of the tube 14 opposite the end in which the jaws are inserted a sleeve 16 is inserted, being internally screw threaded as indicated at 17, to engage threads 15 75 of the jaw members, and provided with a knurled head 18, serving to manipulate the sleeve 16 for exerting tension upon the jaw members and also to abut against the end 80 of the tube 14 to prevent the displacement of the parts.

75 In assembling the device, the abrading members 12 are inserted into the recesses 11, manually, and the jaw members 10 held together temporarily and inserted into the 85 tube 14. The sleeve 16 is now inserted in the opposite end engaging the screw threads 15 of the jaw members and by manual rotation the parts are secured together in the usual well known manner, drawing the jaw 90 members down into the tube 14 and by reason of their divergence as indicated more particularly at Figure 1 serve to clamp the abrading members firmly together. It is 95 obvious, of course, that by manipulating the knurled head 18 and the screw sleeve 16 attached thereto greater or less tension may be exerted upon the abutting, abrading members 12.

100 It is to be understood, of course, that the angle 13, shown at Figure 1, as the angle between the members 12 is in no way controlling as to the angle to be employed and that such angle may be varied to correspond to the preferred angle of grinding 105 of the knife or the like, which is to be sharpened. It is also obvious that the same holder, consisting of the jaws 10, tube 14 and associated parts, may be employed to hold interchangeable abrading members 12 110 having different angles 13, or composed of different material for coarse and fine grind-

ing or for the grinding upon a razor, ordinarily known as honing.

The arrangement of the parts forms a very convenient implement for the purpose and by reason of the ready and convenient interchangeability of the abrading members a number of such abrading members may be furnished with each handle outfit, whereby a complete grinding outfit is provided for different kinds of grinding upon different knives or other cutlery.

What I claim to be new is:

1. A grinding implement comprising a tubular member, jaw members inserted into the tubular member and diverging beyond the end thereof, abrading members retained in abutting position by the diverging portions of the jaw members and presenting a grinding angle, and means to exert tension upon the jaw members.

2. A grinding implement comprising jaw members juxtaposed throughout a portion of their lengths and diverging throughout another portion of their lengths, a tube surrounding the juxtaposed portions, abrading members held between the diverging portions, and means to draw the jaw members longitudinally within the tubular member to exert varied tension upon the diverging portions.

3. A grinding implement comprising a tubular member, a pair of jaw members having abutting portions inserted within the tubular member and having other portions diverging beyond the end of the tubular member, means extending into the tubular member for moving the associated jaw members longitudinally as an organized structure for exerting compressing stress upon the diverging portions, and abrading members held between the diverging portions adjacent their extremities, presenting a grinding angle therebetween.

4. A grinding implement comprising diverging jaw members having sockets formed in their proximate faces adjacent their divergent ends, interchangeable abrading members located in the sockets, a tensioning sleeve, and means to move the tensioning sleeve toward the divergent ends of the jaw members to exert tension upon the abrading members to hold them normally in abutting position with a grinding angle between portions of said grinding members.

In testimony whereof I hereunto affix my signature in presence of two witnesses.

ROCKWELL ADDISON LOOMIS.
